(57) **CLAIM**

The ornamental design for a hair dryer, as shown and described.

DESCRIPTION

FIG. 1 is a perspective view of a hair dryer showing the new design;

FIG. 2 is a front elevational view of the hair dryer of FIG. 1;

FIG. 3 is a rear elevational view of the hair dryer of FIG. 1; FIG. 4 is a left side elevational view of the hair dryer of FIG. 1;

FIG. 5 is a right side elevational view of the hair dryer of FIG. 1;

FIG. 6 is a top plan view of the hair dryer of FIG. 1; and, FIG. 7 is a bottom plan view of the hair dryer of FIG. 1. The dot-dash broken lines show the boundaries of the hair dryer and form no part of the claimed design. The broken line inside/surrounded by the boundary line forms no part of the claimed design.

1 Claim, 6 Drawing Sheets
